UNITED STATES PATENT OFFICE.

GRIFFITH JOHN, OF YONKERS, NEW YORK, ASSIGNOR TO OTIS ELEVATOR COMPANY,
OF JERSEY CITY, NEW JERSEY, A CORPORATION OF NEW JERSEY.

ELEVATOR.

1,141,964.

Specification of Letters Patent.

Patented June 8, 1915.

Application filed August 16, 1912. Serial No. 715,314.

To all whom it may concern:

Be it known that I, GRIFFITH JOHN, a subject of the King of Great Britain, residing in Yonkers, in the county of Westchester and State of New York, have invented a new and useful Improvement in Elevators, of which the following is a specification.

My invention relates to improved means for counterweighting an elevator, and its main object is to compensate for the variations in the extent of the cables on opposite sides of the overhead or guide sheaves.

In elevators it is common practice to counterbalance to a greater or less extent the weight of the car, cage, or platform and its directly attached parts by means of a counterweight connected with the car by a cable or cables passing over suitable guide sheaves located at the top of the hatchway.

While it is possible exactly to counterbalance the car and its average load with a counterbalance weight for a certain given position of the car in the hatchway, there is not a perfect counterbalance for any other position of the car owing to the variations in the extent of the cables upon opposite sides of the overhead or guide sheaves, the greater portion of the cables acting in opposition to the counterweight when the car is at its lower limit of travel, while when the car is at the top of the hatchway the weight of the cables acts in conjunction with that of the counterbalance weight. In order that an elevator may operate efficiently and at uniform speed throughout its entire travel, it has been found necessary to compensate for this varying weight of the cables and the usual method for effecting this result is to connect a chain or chains of the proper weight to the bottom of the car or counterweight, and to secure the opposite ends of said chain or chains to a fixed point in the hatchway midway between the top and bottom, or to connect the bottom of the car and counterweight by chains or ropes. While these arrangements are more or less satisfactory from a theoretical standpoint, there are certain practical objections thereto. For instance, since the chain or chains are supported only at their extreme ends, they are free to thresh about and become kinked, and at best are unsightly and extremely noisy. Furthermore, for certain positions of the car in the hatchway, the entire weight of the compensating chains

must be borne by the hoisting cables. That is to say, when the cables are connected to the bottom of the car and the latter is at the top of the hatchway, the hoisting cables must support the combined weights of the car and its load, the counterweight, compensating chains and the hoisting cables themselves, and when the elevator travels to a considerable height, it is readily seen that this combined weight may reach enormous proportions necessitating a large number of heavy powerful hoisting cables, the cost of which cables alone amounts to considerable.

My invention overcomes all of the above, as well as other objectionable features, in a simple, practical and efficient manner, and the same may best be understood by reference to the accompanying drawing, in which—

Figure 1 represents in elevation an elevator containing an embodiment of my invention; Fig. 2 is a side elevation view of Fig. 1; Figs. 3 and 4 are side and front views, respectively, of a compensating chain; Figs. 5 and 6 are front and rear views, respectively, of a modification.

Referring to the drawing, a cage, car or platform A whatever may be its form or construction, is adapted to move up and down upon suitable guides arranged vertically within the hatchway B under the action of any suitable motive power such as an electric motor M which may be located at the top of the hatchway as shown in Fig. 1, or elsewhere if desired. A traction sheave T is carried upon the shaft of the motor and is grooved to receive one or more cables H which are fastened at one end to the car A and at the other end to an appropriate counterbalance weight W. A sprocket wheel S is carried upon the motor shaft and rotates with it. This sprocket wheel may be of any desired size, but for purposes of illustration I have shown the same just one half the diameter of the traction driving sheave T. A sprocket chain C' is engaged by the sprocket wheel S and each end of this chain is secured to another chain C which is substantially heavier than the chain C' and whose function is to compensate for the variation in the hoisting cables H, the lighter chain C' merely acting as a driving and suspensory means for the chain C. The chain C is somewhat heavier than

twice the weight of the hoisting cables and substantially one half their length and travels at one half the speed due to the 2:1 ratio of the traction sheave and the sprocket wheel S. At the lower bight of the chains C and C' I arrange a guide pulley P which is preferably held under a slight tension by means of a weighted frame F having a limited movement on the guides G secured to the side of the hatchway. The function of the pulley P is to guide the chains C and C' and overcome any tendency for them to sway as the car moves up and down in the hatchway. The sprocket chain C' may be of light construction, of sufficient strength to support the weight of the chain C, and the chain C may be of any desired character provided it has the necessary weight and strength, but is preferably constructed as shown in Figs. 3 and 4 of pivoted links and known as a block chain. A chain of this kind has no lost motion between the links such as is found in a welded link or jack chain, and will run without noise of any kind while at the same time possessing great strength in proportion to its weight.

It will be noted that the weight of the chain C per unit length should be more than twice the weight of the same length of hoisting cable or cables in order to compensate for both the cables and the chain C', that is to say, a foot length of chain C should have a weight equal to twice the weight of a foot length of the hoisting cable or cables plus the weight of a foot length of the sprocket chain C'. With the weights thus proportioned the elevator system will be in perfect balance for all positions of the car with a given load.

Inasmuch as the chains C and C' are suspended from the sprocket sheave S carried by the motor shaft, the hoisting cables are never called upon to support a load other than that of the car and its load, the hoisting ropes and the counterbalance weight. This feature alone is of considerable importance in elevator practice, particularly in the case of a high rise traction elevator. For example, in a traction elevator having a rise of 200 ft. the hoisting cables will weigh in excess of 1500 lbs. using 6 cables of $\frac{5}{8}$ diameter. The usual method for compensating for the weight of cables by hanging chains under the car would subject the hoisting cables to a load in excess of the combined weight of the car, counterbalance weight and weight of the cables by approximately 1500 lbs. when the car is at the upper landing. My invention enables one to move this load of 1500 lbs. from the hoisting cables and place it where it should be, on the hoisting machine, thereby substantially in-

creasing the factor of safety of the hoisting or suspensory cables which of course is most desirable.

65

Referring to the modification as shown in Figs. 5 and 6, it is there seen that the compensating chain C extends the full length of the hatchway and travels at the same speed as that of the car. In this instance the weight of a foot length of chain C will equal the weight of a foot length of hoisting cable or cables plus the weight of a foot length of chain C' which arrangement will compensate for the variation of weight 75 of hoisting cables for all positions of the car.

70

I have shown a 2:1 and 1:1 ratio of travel of the hoisting cables and compensating chain, but it will be understood that other ratios may be employed with equal 80 facility by merely proportioning the diameter of the sprocket wheel S and weight of chain C to suit the new conditions.

85

While I have shown and described the compensating device as a "chain" this term 90 should be considered in its broadest sense, since any arrangement of flexible weights in the form of a series of connected weights or links of which a chain is but one example may be used.

95

It will be observed that the sprocket wheel S may be located at any position upon the shaft of the motor, so as to bring the compensating chain in close to the side of the hatchway out of the way, or if desired the shaft may be lengthened or connected to another shaft having the sprocket wheel thereon, so that the chain can be located entirely outside of the hatchway in some other suitable or desirable place.

100

My invention is herein shown as embodied in a direct drive or traction elevator for simplicity of illustration, and while the invention is particularly adapted to elevators of this character it is also adapted to elevators or other hoists of all descriptions.

105

What I claim is:—

1. In an elevator, the combination of a car, counterweight and connecting cables, and means running at a speed less than that 110 of the cables for counterbalancing the cables without increasing the tension thereon.

2. In an elevator, the combination of a car, counterweight and connecting cables, and means running at a speed less than that 115 of the car for counterbalancing the said cables without increasing the tension thereon.

In testimony whereof, I have signed my name to this specification in the presence of two subscribing witnesses.

GRIFFITH JOHN.
